INVENTOR.
Charles C. Hansen.
BY *Herbert K. Ogden*
HIS ATTORNEY.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

DOUBLE-DRUM HOIST.

Application filed October 10, 1925. Serial No. 61,636.

This invention relates to hoists, but more particularly to a hoist of the double drum type in which either of the drums may be driven from a common driving element.

8 The objects of the invention are to obtain a constant and uniform braking effect on the drums in order to prevent free rotation thereof after the drums have been disconnected from the driving element, to enable 10 the braking mechanism to be readily adjusted and to render the braking element readily accessible for the purpose of inspection and renewal of parts.

15 Other objects will be in part obvious and in part pointed out hereinafter.

The invention consists of the combinations of elements, features of construction, and arrangement of parts having the general mode of operation substantially as hereinafter described and more particularly pointed out in the appended claims and illustrated in the accompanying drawings, in which—

Figure 1 is an elevation partly in section of a hoist constructed in accordance with 25 the practice of the invention,

Figure 2 is a transverse view partly in section taken through Figure 1 on the line 2—2 looking in the direction of the arrows, and

30 Figure 3 is a perspective view of the pawls illustrating the manner in which said pawls are held against relative rotation.

Referring to the drawings, A indicates a base plate which supports at its ends frames 35 B and C. The frames B and C may be secured to the base plate A in any suitable manner and are connected rigidly at their tops by a tie-rod D which is threaded at its ends to receive suitable nuts E.

40 Formed integrally with the frame C is a box F which forms a mounting for a motor G. The motor G is in this instance of the square cylinder type in which one piston is adapted to reciprocate within another piston. Accordingly a piston H reciprocates 45 transversely within a cylinder J and a second piston K is arranged to reciprocate vertically within the piston H. In this way the combined movements of the pistons H and K are resolved into a rotary movement 50 for rotating a driving shaft L which in this instance is connected to the piston K by means of a crank pin O. Since the motor illustrated in the drawings forms no part 55 of the present invention and its construction

and operation are well understood, further description thereof is considered unnecessary, and it is to be understood that any suitable reversible motor of compact type may be used for rotating the main driving 60 shaft L.

In the present instance, the main driving shaft L is supported at one end by the frame C and extending longitudinally through the hoist is supported at its other end by the 65 frame B. Encircling the driving shaft L is a center bearing P also supported by the frames B and C and which forms a support for a haulage drum Q and a tail rope drum R mounted side by side and adapted to rotate upon the center bearing P. On adjacent sides of the drums Q and R are formed flanges S and T respectively which carry drum drivers U and V. The drum drivers U and V are in the form of teeth having opposed engaging faces, and, if desired, may be formed separately and secured to the flanges S and T in any convenient manner.

Arranged rotatably on the center bearing P and between the drums Q and R is a 80 main driver W preferably in the form of a spur gear which meshes with a pinion X keyed to a counter shaft Y. The counter shaft Y in this instance is provided with anti-friction bearings Y' and Y² supported 85 by the frames B and C respectively and projects at one end into a gear casing Z preferably formed integrally with the frame B. A cover B' which may be secured firmly to the frame C in any suitable manner serves to hold the bearing Y² in the frame B and forms a pocket or reservoir for oil or other lubricant for the bearing Y². A gear b is keyed to the shaft Y to mesh with an intermediate pinion c formed integrally with 90 a shaft d and supported at one end by the frame B and at its other end by a plate e which forms a cover for the gear casing Z. Keyed to the shaft d adjacent the pinion c is an intermediate gear f which meshes 95 with a driving pinion g keyed to the main driving shaft L.

A boss h is formed on the main driver W and is bored to receive a bushing j having an inwardly extending flange k intermediate 105 its ends. Disposed within the bushing j are a pair of pawls o and p having trunnions q and r which extend rotatably into the bushing j and thus provide pivots for said pawls. Clutch members s preferably 110

semi-circular shape, are formed on the trunnions *g* and *r* to interlock with each other when the pawls are in their normal position so that the pawls *o* and *p* will be simultaneously rocked about their pivot. The portions comprising the clutch members *s* are in this instance of smaller diameter than the trunnions *g* and *r* thus forming shoulders *u*, which, when the pawls are in their proper position in the bushing *j*, will abut the flange *k* and thus prevent the trunnions from sliding longitudinally within the bushing *j*. The pawls *o* and *p* in this instance are identically alike so that if one of the pawls is subjected to harder usage than the other pawl, as is frequently the case, the pawls may be interchanged.

In order to clamp or hold the clutch members *s* constantly in engagement with each other, a bolt *v* is extended through said trunnions and has a nut *w* for clamping said pawls in relative position. The boss *h* and the bushing *j* are in this instance relieved as at *x* to permit free oscillation of the pawls. In this way a shoulder *y* is formed rearwardly of each pawl to form a support for the pawls when said pawls engage the drum drivers.

Suitable brakes are usually provided in hoists of this type for preventing free rotation of the drums when they are disconnected from the driving element. In the present instance, semi-circular bands *z* are arranged to bear against the flanges *S* and *T*, preferably beneath said flanges, and carry at their ends screws 2 and 3. The screw 2 is provided with a pair of adjusting nuts 6 and extends through a bracket 4 preferably pivoted on a yoke 5, which yoke in this instance, is supported by the rod *D* to partly encircle the main driver *W* and is held against endwise movement by suitable spacers *D'* interposed between said yoke and the end frames *B* and *C*. In order to hold the yoke 5 against oscillatory movement on the rod *D* one end of the yoke is secured to an arm *A'* formed on the base *A*. The other end of the yoke is supported by a strap *C'* secured to the base *A* by bolts *C*. The means whereby the yoke 5 is secured to the strap *C'* may be a suitable pin *C* which also forms a pivot for the bracket 4. The screw 3 extends through the yoke 5 and like the screw 2 is screw threaded at its free end to receive a thumb nut 7 whereby the band *z* may be tightened.

In the operation of the hoist, assuming that the driving shaft *L* is being rotated in a counter-clockwise direction, rotary motion of the shaft in this direction will be transmitted through the train of gearing in the gear casing *Z* and the pinion *X* and will cause the main driver *W* to rotate in a clockwise direction. With the main driver *W* rotating in this direction, the pawl *o* will be

forced into engagement with the drum driver *V* and rotate the drum *R* with said main driver. Upon reversal of the main driving shaft *L* the direction of rotation of the main driver will also be reversed, thus disconnecting the pawl *o* from the drum driver *V* and simultaneously actuating the pawl *p* into engagement with the drum driver *U* on the drum *Q* and rotate said drum with the main driver.

From the foregoing it will be seen that the direction of rotation of either drum is at all times counter to the direction of rotation of the main driving shaft *L*.

After one or the other of the drums have been disconnected from the main driver, said drums will be held against free rotation by the braking action of the bands *z*, it being understood that the bands *z* are preferably so adjusted as to exert a constant braking effect on the flanges *S* and *T*. Whenever the brake bands *z* become somewhat worn, they may be readily adjusted to grip the flanges more closely by merely screwing down the thumb nuts 7 on the screws 3. By this form of construction, the braking mechanism is at all times accessible for purposes of inspection and new parts may be substituted for worn parts with a minimum expenditure of time.

I claim:

1. In a hoist, the combination of a reversible motor, a driving shaft connected to be rotated by the motor, end frames supporting the driving shaft, a pair of drums rotatable about the driving shaft, a main driver between the drums connected to be rotated by the driving shaft, clutch members carried by the main driver for selectively connecting one or the other of the drums to be driven by the main driver, flanges carried by the drums, a tie rod connecting the end frames, a yoke supported by the tie rod, and braking means pivoted to the yoke to exert a braking effect on the flanges for checking the rotation of the drums upon the release of the drums from the main driver.

2. In a hoist, the combination of a reversible motor, a driving shaft connected to be rotated by the motor, end frames supporting the driving shaft, a pair of drums rotatable about the driving shaft, a main driver between the drums connected to be rotated by the driving shaft, clutch members carried by the main driver for selectively connecting one or the other of the drums, a tie rod connecting the upper ends of the end frames, a yoke supported by the tie rod partly encircling the main driver, means for preventing oscillation of the yoke, and brake bands pivoted to one end of the yoke to act constantly against the flanges for preventing free rotation of the drums when one or the other of the drums is released from the main driver.

3. In a hoist, the combination of a reversible motor, a driving shaft connected to be rotated by the motor, end frames supporting the driving shaft, a pair of drums 5 rotatable about the driving shaft, a main driver between the drums connected to be rotated by the driving shaft, clutch members carried by the main driver for selectively connecting one or the other 10 of the drums to be driven by the main driver, flanges on adjacent ends of the drums, a tie rod connecting the upper ends of the

end frames, a yoke supported by the tie rod partly encircling the main driver, means for preventing oscillation of the yoke, and semi-¹⁵ circular brake bands pivoted to the yoke extending beneath the flanges to act constantly against the flanges for preventing free rotation of the drums when the drums are disconnected from the main driver. ²⁰

In testimony whereof I have signed this specification.

CHARLES C. HANSEN.
